(57) **CLAIM**

The ornamental design for a leash for animals, as shown and described.

DESCRIPTION

FIG. 1 is a perspective view of a leash for animals showing the new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of detail “9” identified in FIG. 1; and,

FIG. 10 is an enlarged view of detail “10” identified in FIG. 2.

The broken lines in the drawings illustrate portions of the leash for animals which form no part of the claimed design.

1 Claim, 10 Drawing Sheets
